UNITED STATES PATENT OFFICE.

WILLIAM H. SMITH, OF ST. PAUL, MINNESOTA.

TANK FOR GASOLINE-ENGINES.

1,083,413.

Specification of Letters Patent.

Patented Jan. 6, 1914.

Application filed August 5, 1912. Serial No. 713,313.

To all whom it may concern:

Be it known that I, WILLIAM H. SMITH, a citizen of the United States, residing at St. Paul, in the county of Ramsey and State of Minnesota, have invented a new and useful Tank for Gasolene-Engines, of which the following is a specification.

My invention relates to gasoline tanks for use in connection with gasoline engines whether stationary or movable as in marine engines, boats, automobiles, auto trucks and so forth.

The object of the invention is to provide a tank with means for separating from the gasoline all water or other impurities before the gasoline leaves the tank and is used as a gas producing agent in the engine.

In the accompanying drawing Figure 1 is a side elevation of my improved gasoline tank. Fig. 2 is a bottom view of the tank shown in Fig. 1. Fig. 3 is an enlarged diametrical section on the line *a—a* in Figs. 1 and 2 with a pet-cock added. Fig. 4 is a top view of filter shown in the middle of Fig. 3. Fig. 5 is a section about as on the line *b—b* Fig. 2 on an enlarged scale of a modification of the water separating device.

Referring to the drawing by reference numerals, 1 designates the main gasoline tank for a gasoline engine. The top of the tank is provided with a cover 2 of any suitable construction. The bottom 3 of the tank inclines toward one side of the tank so that any water contained in the gasoline or other gas producing fluid in the tank will gradually sink and move to the lowest part of the bottom and is there permitted to pass through a tube 4 into a water pocket or compartment 5, which may be suspended by said tube 4 and another tube 6, or it may be secured directly to the tank 1, as in Fig. 5, thus dispensing with the tube 6, leaving only the aperture 7 in the bottom 3. The tube 4 preferably extends considerably downward into the water receptacle, as clearly shown in Figs. 1, 3 and 5, so that the water is guided by the tube to the bottom of the receptacle while the gasoline gradually escapes upward through the aperture 7 and tube 6 when the latter is used.

8 is a pet-cock for emptying the water out of the receptacle 5 one or more times a year as may be required. Of said cock only the tube 9 is shown in Figs. 1, 2 and 5.

55 The bottom 3 of the main tank has preferably a central aperture 10 surrounded by

a fixed screw threaded collar 11, upon which is screwed a cap 12 having a central opening 13. Within said cap is provided a ring 14, whose lower side is covered by a piece 60 of chamois skin 15 and its upper side by a similar piece 16, both of which are clampingly held one between the ring and the cap, the other between the ring and the bottom 3 near around the opening 10. Below said opening is secured to the bottom 3 a compartment 17 having in its bottom a nipple 18 from which the gasoline is supplied to the mixing chamber of the engine through suitable piping (not shown).

In the use or operation of the device the gasoline is poured into the main tank 1 and is filtered by passing through the chamois 16 and 15 into the lower receptacle 17 while the precipitated water, dust and dirt which can not pass through the chamois, or fall beyond the same, find their way down into the receptacle 5, the agitation of the gasoline in most engines preventing even the dust and sand from lodging upon the filter, especially as the latter is inclined the same as the bottom 3.

One of the many modifications which are unnecessary to specify, as they come within the scope and spirit of the invention, is the omission of the tube 6 and even the aperture 7 since by making the tube 4 wide and short the gasoline in the receptacle 5 may escape upward through the same opening that permits the water to enter said receptacle.

What I claim is:

1. In a gasoline tank for engines, the combination with a main gasoline compartment having a bottom with an aperture in it, of a lower gasoline compartment below said aperture and provided with an outlet from which to feed gasoline to the engine, and a filtering means covering the aperture in the bottom of the main tank, said filtering 95 means consisting of a removable screw cap having a central opening, a ring within the cap and two filtering sheets, one of which is clamped between the ring and the cap, the other between the ring and the main bottom 100 around the aperture therein.

2. In a gasoline tank for engines, the combination with a main gasoline compartment having a bottom with an aperture in it, of a lower gasoline compartment below said aperture and provided with an outlet 110 from which to feed gasoline to the engine,

and filtering means covering the aperture in the bottom of the main tank, said bottom being inclined and at its lowest point provided with an aperture, a receptacle fixed 5 below said aperture and communicating therewith, and means for emptying said receptacle through its bottom, a tube extending from said aperture toward the bottom of the receptacle, and means for permitting

the gasolene in the receptacle to escape upward into the main tank when water accumulates in the receptacle.

In testimony whereof I affix my signature, in presence of two witnesses.

WM. H. SMITH.
